UNITED STATES PATENT OFFICE.

JOHN R. FLETCHER, OF DAYTON, OHIO.

DESIGN FOR A POLE FOR ELECTRIC WIRES.

SPECIFICATION forming part of Design No. 20,449, dated January 6, 1891.

Application filed September 30, 1890. Serial No. 366,688. Term of patent 14 years.

To all whom it may concern:

Be it known that I, JOHN R. FLETCHER, a citizen of the United States, and a resident of Dayton, in the county of Montgomery and State of Ohio, have invented and produced a new and original Design for Poles for Electric Wires and the Like, of which the following is a specification.

My design is illustrated in the accompanying drawings, wherein—

Figure 1 represents a side view of the pole; Fig. 2, an end view.

The leading features of my design consist in a pole of relatively very thin diameter in one direction and of a gently-tapering side elevation. The pole is designed to set at the side of the street, with the flat wide surface at right angles to the length of the street. Thus, when seen while looking down or up the street, the poles will appear as a succession of upwardly-diminishing flat surfaces, while when any one pole is viewed from the

sidewalk looking toward the street it will be so narrow as to present no obstruction to the vision, and may also be rounded, as shown. 25

Referring to the drawings, in which both figures are alike, A A are the side sheets or strips of gradually-diminishing widths toward the top, while B B are the end strips, which, together with the side strips, make up the pole. 30 They may be rounded on the surfaces, as shown.

C are brackets which support the projecting arms D D. These brackets are triangular, as shown, and ornamented with checker 35 or grid work.

What I claim is—

The design for a pole for supporting wires and the like, substantially as shown.

JNO. R. FLETCHER.
